DESIGN FOR A HEATER

Lewis W. Welch, Detroit, Mich., assignor to Novi Equipment Company, Novi, Mich., a corporation of Michigan

Application April 2, 1941, Serial No. 100,106

Term of patent 3½ years

To all whom it may concern:

Be it known that I, Lewis W. Welch, a citizen of the United States of America, residing at Detroit, in the county of Wayne and State of Michigan, have invented a new, original, and ornamental Design for a Heater, of which the following is a specification, reference being had therein to the accompanying drawing, forming a part thereof, wherein:

Figure 1 is a top plan view of a heater embodying my new design;

Figure 2 is a side elevational view thereof;

Figures 3 and 4 are elevational views of opposite ends of the heater.

The characteristic feature of my design resides in the combination on the heater disclosed of the stepped circular perforated grille on the top wall, and the specific motor housing on the bottom wall in association with the heater casing, as shown.

I claim:

The ornamental design for a heater, as shown and described.

LEWIS W. WELCH.
